UNITED STATES PATENT OFFICE.

CHESTER B. MUMMERT, OF HARRISBURG, PENNSYLVANIA.

RING CLAMP.

Application filed January 20, 1926. Serial No. 82,541.

This invention relates to improvement in clamps for use upon pistons in compressing the piston ring within the grooves defined therein to permit the insertion of the pistons and rings within cylinders.

Another object of my invention resides in the specific construction of the clamp being relatively wide and split having one end of a relatively narrow strip pivotally secured adjacent one end thereof and extending across its opposite and adjacent end and including an elongated slot with alternately arranged cutout portions provided in its adjacent side edges for selective engagement with the headed stud provided on the clamp for compressing and locking the rings precedent to their insertion, with the piston, within a cylinder bore.

With the above and other objects in view, the invention further includes the following novel features and details of construction, to be hereinafter more fully described, illustrated in the accompanying drawings and pointed out in the appended claims.

25 In the drawing:—

Figure 1 is an elevation of a piston with my invention applied thereto.

Figure 2 is a top plan view thereof.

Figure 3 is an elevation of the piston with the invention applied thereto when inserted within a cylinder.

Referring to the drawing in detail, wherein like characters of reference denote corresponding parts, the reference character 10 indicates a piston and 11 a plurality of piston rings fitted within the usual grooves defined therein, all of the above being of the usual and well known construction and forming no part of the present application for Letters Patent but being merely shown for purposes of illustrating in bringing forward the novel advantages of the above entitled invention.

The invention resides in the provision of a relatively wide and thin split metallic clamp or band such as indicated at 12 having one end of a relatively narrow strip 13 pivotally mounted as indicated at 14 adjacent one end and extending a major portion of its length along and against the opposite end of the band or clamp, as clearly illustrated in Figure 1 of the drawing. A relatively narrow band 13 further includes an elongated slot 15 therein with a plurality of alternately arranged cutout

portions 16 within its opposite side edges for selective reception of a headed stud 17 therein mounted upon the outer side of the corresponding end of the clamp or band 10 and in direct alignment with a horizontal 60 plan with respect to the relatively narrow band 13 and the elongated slot 15 provided therein.

In the use and operation of the present invention it is clearly apparent and manifest that upon the partial insertion of the piston 10 within the cylinder bore having walls 18 of a block 19 and upon application of the band or clamp 12 upon the rings 11 of the piston 10 in compressing said rings 70 11 to correspond with the diameter and circumference with the cylinder bore 18, as clearly illustrated in Figure 3 of the drawing that the piston 10 with the rings 11 mounted thereon may be readily and easily 75 pushed downwardly within the cylinder bore 18; the lower edges of the band or clamp 12 engaging the upper marginal edges of the cylinder bore 18 of the block 19 and exerting the desired pressure against 80 each successive ring as the latter is forced within the cylinder bore 18.

It is further to be noted that the invention may be applied equally and effectually as well upon pistons having rings adjacent 85 their lower ends and automobiles having large bearing boxes will permit the said pistons to be shoved and fitted within their cylinder below and obliterate the necessity of removing the cylinder head of the motor in accomplishing the result of inserting the pistons and rings within the cylinders therefor.

The invention is susceptible of various changes in its form, proportions and minor 95 details of construction, and the right is herein reserved to make such changes as properly fall within the scope of the appended claims.

Having thus described the invention, what 100 is claimed is:—

1. A clamp for use upon rings and pistons therefor comprising a relatively wide split band bent in accordance with the configuration of the piston, a relatively narrow band pivotally mounted adjacent one end of the band and having its opposite end extending across the opposite end thereof, and means provided upon the opposite end of the relatively wide band for locking the relatively 110

narrow band in a desired position upon the first mentioned band to compress the rings upon the piston.

2. A clamp for use upon rings and pistons therefor comprising a relatively wide circumferentially split band, a relatively narrow arcuate-shaped band having one end pivotally mounted adjacent one end of the first mentioned band and having its opposite 10 end extending the major portion of its length across the opposed end of the relatively wide band, the relatively narrow band including an elongated slot therein with cut-

out portions disposed in staggered relation within its opposite side edges, and a headed ¹⁵ stud mounted upon the outer side of the corresponding end of the relatively wide band and adapted for selective engagement within any one of a plurality of the cutout portions in the relatively narrow band for compressing the rings to permit the piston and rings therefor to be readily and easily fitted within the bore of the cylinder block.

In testimony whereof I affix my signature.

CHESTER B. MUMMERT.
